UNITED STATES PATENT OFFICE.

ALBERT BERAN, OF HIRSCHWANG, AUSTRIA-HUNGARY.

METHOD OF MAKING PULLEYS.

SPECIFICATION forming part of Letters Patent No. 771,696, dated October 4, 1904.

Application filed September 8, 1903. Serial No. 172,386. (No model.)

To all whom it may concern:

Be it known that I, ALBERT BERAN, a subject of the Emperor of Austria-Hungary, residing at Hirschwang, in the Province of Lower Austria, in the Empire of Austria-Hungary, have invented certain new and useful Improvements in Methods of Making Pulleys; and I do hereby declare the following to be a full, clear, and exact description of the invention, such as will enable others skilled in the art to which it appertains to make and use the same, reference being had to the accompanying drawings, and to letters and figures of reference marked thereon, which form a part of this specification.

My invention has relation to the manufacture of pulleys, and more especially to the manufacture of pulley-rims for split pulleys made from a block or slab of suitable material in such manner as to obtain a plurality of concentric rims of successively decreasing diameter.

In the accompanying drawings, Figure 1 is a plan view of a block or slab of material. Fig. 2 is a face view of the pulley-rim of greatest diameter cut from said block, and Fig. 3 is an elevation of a completed pulley.

In carrying out my invention I take, for instance, a block of material *a* of uniform thickness and make a cross-cut 1, extending from one edge of the block equidistant from two of its corners to the center of said block, and I then divide the block into concentric rings *b*, *c*, *d*, and *e* by circular concentric cuts 2, 3, 4, 5, and 6, starting from and returning back to the cross-cut 1. It is obvious that the waste of material is here reduced to a minimum, as but a small portion of the block outside of the pulley-rim 2 and the small central portion of the block *a* are wasted. On the other hand, considerable time and labor is saved in making these pulley-rims, as a gang of suitable band-saws can be used to divide the block *a* at one operation. By the method described I obtain a series of pulley-rims of uniform width of face and, if desired, of uniform thickness, but of successively-reduced diameters, all split at one point. These rims are then split on a line diametrically opposite the cut or split 1 for the manufacture of split

pulleys. I next mortise the rim to receive tenons on the ends of arms of a half-hub or, preferably, cut transverse dovetailed grooves 7 in each half-rim near its terminal edges 1 for corresponding tenons on arms or spokes 55 *s* of two half-hubs *h* and *h'*, which are bolted together by bolts *b'*, suitable washers being interposed between the heads at one end of the bolts and the tightening-nuts at the opposite end.

The rims may, if desired, be separately finished in any usual manner, or the pulley when provided with its hub may be so finished.

I prefer to make the blocks of a number of square pulp sheets or boards, as millboard or 65 pasteboard, glued or otherwise cemented together and subjected to the required pressure to form a solid, hard, and homogeneous block in a well-known manner, the number of sheets or boards used depending of course upon the 70 width of the face of the pulley-rims to be cut therefrom. I prefer this material not only because it is possible to obtain a solid, hard, and homogeneous, yet comparatively light block, but because of the frictional re- 75 sistance offered by this material to the driving-belt, preventing the slipping of the belt, and consequently undue heating, and insuring a more uniform angular movement of the pulley.

Having thus described my invention, what I claim as new therein, and desire to secure by Letters Patent, is—

1. The method of making pulley-rims, which consists in making a cross-cut extending from one edge to the center of a block of material and dividing the block into pulley-rims by concentric circular cuts from and back to the aforesaid cross-cut, substantially as set forth.

2. The method of making pulley-rims, which consists in making a cross-cut extending from one edge to the center of a block of material, then dividing the block into pulley-rims by concentric circular cuts from and back to said cross-cut and dividing the split rims so obtained into half-rims on a line with the cross-cut, substantially as set forth.

3. The method of making pulley-rims, which consists in making a cross-cut extend-

ing from one edge to the center of a block of material, dividing said block into pulley-rims by concentric circular cuts from and back to said cross-cut, dividing the split rims thus obtained into half-rims on a line with the aforesaid cross-cut and forming seats in said half-rims for the spokes of a divided hub, substantially as set forth.

4. The method of making pulley - rims, 10 which consists in making a cross-cut extending from one edge and equidistant from opposite corners to the center of a square block of material, dividing said block into pulley-rims by concentric circular cuts from and back to said cross-cut, and dividing the split rims thus obtained into half-rims on a line with the cross-cut, substantially as set forth.

5. The method of making pulley - rims, 20 which consists in forming a square block by uniting under pressure a suitable number of pulp-boards, making a cross-cut from one edge and equidistant from opposite corners to the center of said block and dividing the latter into pulley-rims by circular concentric cuts from and back to the cross-cut, substantially as set forth.

6. The method of making pulley - rims, 25 which consists in forming a square block by

uniting under pressure a suitable number of pulp-boards, making a cross-cut from one edge 30 and equidistant from opposite corners to the center of said block, dividing the latter into pulley-rims by circular concentric cuts from and back to the cross-cut, and dividing the split rims thus obtained into half-rims on a 35 line with the aforesaid cross-cut, substantially as set forth.

7. The method of making pulley - rims, 40 which consists in forming a square block by uniting under pressure a suitable number of pulp-boards, making a cross-cut from one edge and equidistant from opposite corners to the center of the block, dividing the block into pulley-rims by circular concentric cuts from and back to said cross-cut, dividing the split 45 rims into half pulley-rims on the line of the cross-cut and forming seats in the inner face of said half-rims for the spokes of a divided hub, substantially as set forth.

In testimony that I claim the foregoing as 50 my invention I have signed my name in presence of two subscribing witnesses,

ALBERT BERAN.
